UNITED STATES PATENT OFFICE.

WARREN J. KIRBY, OF INSPIRATION, ARIZONA.

DIE APPARATUS.

Application filed December 14, 1927. Serial No. 239,989.

This invention relates to a die apparatus, and has for its object the construction of a simple and efficient apparatus for making rock drill bits very similar to that shown in my United States Patent No. 1,627,909, issued May 10, 1927.

Another object of the invention is the construction of an apparatus which will operate upon a hot drill, having an inclined or bevelled end, to produce on said drill an off-set, constituting preferably a curved cutting point such as is shown in my above specified patent.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in side elevation of an apparatus constructed in accordance with the present invention, while

Figure 2 is an end view, in elevation, of the drill-receiving end.

Figure 3 is a sectional view taken on line 3—3, Figure 2, and looking in the direction of the arrows.

Figure 4 is a sectional view taken on line 4—4, Figure 3, and looking in the direction of the arrows.

Figure 5 is an end view, looking at the inner end of the barrel and shaping pin.

Figure 6 is a longitudinal sectional view of the cam roller and its stub shafts.

Figure 7 is a transverse sectional view of the bed plate and a shim.

Figure 8 is a top plan view of the shaping pin, while

Figure 9 is an inner end view of the same.

Figure 10 is a bottom plan view of the shaping pin, while

Figure 11 is an inner end view of the same.

Figure 12 is a view in side elevation of the shaping pin, while

Figure 13 is an inner end view of the same.

Referring to the drawings by numerals, 1 is the base plate upon which is placed the bed plate 2, which bed plate is slightly dished at 3 to better accommodate the hot drill 4 (dotted lines). Between the bed plate 2 and base plate 1, I place one or more shims 5, for the purpose hereinafter described. Suitably bolted to the bed plate 1 are two "angles" or

uprights 6. A cam roller 7, provided with stub shafts 8 is journalled upon the uprights 6, and to one of said stub shafts 8 is fastened an operating handle 9. The cam roller 7 is for the purpose of tightly holding the drill 4 within the apparatus while the drill is being formed with my peculiarly constructed cutting point.

A casing 10 is secured upon the base plate 1, and fastened or mounted within casing 10 is barrel 11. Mounted in barrel 11 is shaping pin 12. Apertures 13 are formed in the top of the casing 10, whereby a suitable lubricant can be supplied to the interior of the casing.

The shaping pin 12 is provided at its inner end with an inclined wall 14, and extending outwardly from this end, at opposite sides of the shaping pin is a pair of wings 15. The top of the shaping pin, at the inner end, projects, forming a top wing 16. Extending outwardly from the inclined wall 14 is a V-shaped spur 17; this spur serves to keep open the inner end of the longitudinally extending water passage 18 (dotted lines), shown in Figures 1 and 3, and more particularly disclosed in my aforementioned United States Patent No. 1,627,909.

The heated drill, or drill bit 4 is run into the apparatus under cam roller 7, until the inner end of the drill is engaged by the barrel 11 and the shaping pin. Then the cam roller is rotated to clamp tightly upon the drill, holding the drill securely in the apparatus during the forming operation. Force is applied to the outer end of the barrel 11 and shaping pin 12, which causes an off-set 19 (dotted lines), Figure 3, to be formed upon the drill; the side wings 15 keep the drill from spreading laterally, whereas the top wing 16 keeps the drill from spreading upwardly, hence as force is applied to the barrel and shaping pin, the extreme inner end of the drill is bent or forced downwardly, producing the curved off-set end, clearly shown in my Patent No. 1,627,909. The thickness or size of the off-set is controlled by the number of shims 5 that are placed under the bed plate 2; if only one is placed, as shown in the drawings, then the off-set will be less than if two or more shims are placed under the bed plate. Therefore, it will be seen that I have provided means for making different size off-sets, of my peculiar structure, upon drills or drill bits for the purpose of drilling different size holes.

The bed plate is provided with a plurality

of vertical apertures 20, and each shim 5 is also provided with registering apertures 21, Figure 7. Suitable fastening means such as pins 22 extend up from the base plate through apertures 20 and 21, detachably holding the bed plate and shim in an efficient operative position. It will be understood that as many shims as desired can be held in position by pins 22; the number of shims being dependent upon the size of the off-set desired on the finished product.

The shaping pin forces the cutting end of the bit to assume an elliptical shape; the wings of said shaping pin serve to keep the cutting end of the bit from being forced in the wrong direction, and the spur 17 prevents the water passage 18 from being closed at its inner end, while the barrel 11 and shaping pin 12 are being driven inwardly, within 15 the stationary casing 10 during the formation 20 of a finished drill or bit.

The shim, or shims 5 constitute detachable adjusting means for lifting the bed plate for controlling the size of the off-sets on the finished cutting end of the drill or bit.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall

fairly fall within the scope of the appended claims.

What I claim is:

1. In an apparatus of the class described, the combination with a base plate, of a casing provided with a lubricant receiving aperture on said base plate, a barrel slidably mounted within said casing, a shaping pin fixedly mounted in said barrel, said shaping pin provided with an inclined wall at one end, a V-shaped spur extending from said inclined wall, said shaping pin provided at said end with side wings and a top wing extending beyond said inclined wall, and said base plate provided with means for holding a drill in position to be operated upon by said barrel and shaping pin.

2. In an apparatus of the class described, the combination with a base plate, of a casing on said base plate, a sliding barrel and shaping pin within said casing, said shaping pin provided at one end with an inclined wall 55 within the end of the barrel, said shaping pin provided with an outwardly extending spur, and also with outwardly extending wings, said wings extending to the inner end of said barrel, and means for holding a drill on said 60 base plate in position to be operated upon by said barrel and shaping pin.

In testimony whereof I hereunto affix my signature.

WARREN J. KIRBY.
